CHAIR OR THE LIKE

Jeffrey Owen Brosk, 150 E. 69th St.,
New York, N.Y. 10021

Filed Sept. 2, 1967, Ser. No. 8,575

Term of patent 14 years

Int. Cl. D6—01

U.S. Cl. D15—1

FIG. 1

FIG. 3

FIG. 2

FIG. 4

FIG. 1 is an exploded view of a chair showing my new design.

FIG. 2 is a plan or top view thereof with the seat cushion in position.

FIG. 3 is a perspective view thereof showing sides and top; and

FIG. 4 is a front perspective view of the chair, a figure being shown thereon in dotted outline for illustrative purposes only.

I claim:

The ornamental design for a chair or the like, as shown and described.
